CLAIM

The ornamental design for rack for cooking appliance, as shown and described.

DESCRIPTION

FIG. 1 is a perspective view of a rack for cooking appliance showing our new design;

FIG. 2 is a front view thereof;

FIG. 3 is a right side view thereof;

FIG. 4 is a left side view thereof;

FIG. 5 is a bottom view thereof;

FIG. 6 is a top view thereof; and,

FIG. 7 is a rear view thereof.

The broken lines represent environment or structure of the display panel, fitting or accessory for a cooking appliance and form no part of the claimed design.
